To all whom it may concern:

Be it known that I, JOHN W. MCKENZIE, a citizen of the United States, residing at Toledo, in the county of Lucas and State of Ohio, have invented and produced a new and original Design for the Shell of a Clamp for Bicycle-Saddle Springs, &c., of which the following is a specification, reference being had to the accompanying drawings, forming a part thereof.

My invention relates to the shell or body of a clamp for bicycle-saddle springs, &c.; and my invention consists in the new and original design for the shell of a clamp, as will be hereinafter fully described.

Referring to the drawings, Figure 1 is a top or bottom view of a clamp-shell, showing my design; and Fig. 2 is a side view of the clamp-shell shown in Fig. 1, looking in the direction of arrow a, same figure.

The leading feature of my design for a clamp-shell consists of a hollow body portion which is tapered or beveled from its center toward its ends to form a substantially elongated diamond shape in side view or elevation, as shown in Fig. 2, with a projection or extension on one end.

In the drawings, 1 is a clamp-shell of my design, which is tapered or beveled from its center toward each end to form a substantially elongated diamond shape in side view or elevation, as shown in Fig. 2, and 2 is a projection or extension on one end.

What I claim is—

A design for the shell or body of a clamp for bicycle-saddle springs, &c., substantially as shown and described.
